UNITED STATES PATENT OFFICE.

WILLIAM F. SCHACHT, OF HUNTINGTON, INDIANA.

GAME APPARATUS.

Application filed February 3, 1926. Serial No. 85,675.

This invention is a novel improvement in game apparatus which may be either used in quoits, or horse-shoe pitching games, the game being played by pitching rings, quoits, or horse-shoes over pins.

The object of the present invention is to provide a game of this character which can be safely played in-doors, on tables, or floors, without injury thereto and without injuring adjacent pieces of furniture. The present invention has particular reference to the standard or pin member of the game and means for supporting same in operative position, and further provides novel supports having supplemental shorter pins over which rings or horse-shoes may be thrown or pitched, the pins having certain numerical relation to each other, so that the total number of points made by the player would depend upon the number of times he "rings" the various pins. The invention in brief comprises a base or support for the pin, preferably made circular or disk-like in shape, and of rubber, also having the features of construction hereinafter referred to, and also having a central pin support projection or boss on its upper side, and a plurality of equidistant spaced stub pins or studs on its upper side adjacent its periphery spaced equidistant from the central boss. Rising from the central boss is a pin preferably of metal and preferably attached to or engaged with the boss, as hereinafter explained.

In the accompanying drawings I have illustrated one preferred form of the game device and will explain the same with reference thereto to enable others to adopt and use the invention, and will refer to the claims for summaries of the essential features and construction of parts for which protection is desired.

In said drawings—

Fig. 1 is a perspective view of a portion of the game apparatus embodying the invention.

Fig. 2 is a central vertical sectional view thereof on the line 2—2, Fig. 1.

Fig. 3 is a vertical sectional view of a modified form of base.

Fig. 4 is a detail of the central boss.

The base 1 shown in the drawings is preferably circular or disk-shaped and formed of vulcanized rubber, and it also preferably is formed with a thickened annular marginal portion 1^a, and a central annular

thickened portion 1^c connected with the outer annular portion 1^a by a thinner pliable web portion 1^b, which insures that the base will firmly adhere by suction to the flat surface on which it is placed. The central portion 1^c is provided with a central annular projection 1^d which is preferably formed integral with the portion 1 and is provided in its upper side with an axially disposed vertical socket 1^e, into which is adapted to be fitted the lower end of a pin 2, preferably metallic, and the lower end of the socket 1^e is provided with an interior enlargement or recess 1^f which is adapted to accommodate an enlarged head 2^f on the lower end of the pin 2. The diameter of the socket 1^e is preferably somewhat smaller than the diameter of the pin 2 in order that the boss will close around the pin 2 owing to the resiliency of the rubber and retain the pin in the socket by the resiliency of the rubber. This construction enables the pin to be detached from the base for convenience in transporting or packing the game, but the pin can be engaged with the base by forcing its head through the socket until the head engages the recess 1^f, whereupon owing to the resiliency of the rubber the boss will close around the pin and engage the shank of the pin and securely retain the same in position as shown in Figs. 1, 2 and 3, and this construction which enables the pin to be readily assembled instead of being permanently attached to the base, is one of the practical valuable features of the invention.

In some cases the pin might be secured to the base in various other ways, within the broader aspect of the invention, but the preferred form of the invention is to have the base molded with an enlarged recess 1^f and the pin formed accordingly with a head 2^f on its end adapted to detachably engage the recess in the manner above described. If desired the enlarged portion 1^f of the socket 1^e may be omitted, and a pin having no head 2^f on its lower end inserted in the socket 1^e, in which case since the diameter of socket 1^e is smaller than the pin 2, the pin would be retained in the socket by the resiliency of the material of the boss, and also by the suction at the lower end of the socket produced when the pin 2 is inserted in the socket.

A further novel feature of the invention is having the base provided with a plurality of stub pins or projections 3 which

are preferably spaced equidistant between centers on the top of the part 1^a of the base, and are preferably formed integral therewith, these studs 3 being preferably smaller in diameter than the central stud 1^a, and projecting sufficiently above the surface of the disk to permit engagement by a ring, quoit, or horse-shoe, which might be pitched thereover in case such quoit, ring, or horse-shoe should not engage the pin 2. In practice three or four studs would ordinarily be enough and of course their number might be varied. In playing the game these different studs 3 may have the same or different value, preferably having different numerical values, the numerical value of the studs 3 being less than the numerical value of the pin 2. For example, the pin might have a numerical value of 25 and the studs 20 have a numerical value of 5, 10, 15, 20, respectively, and the game being determined upon the number of points made, say 100, the number of points made at each play by the player depending upon the particular 25 studs engaged by the rings.

The rings, quoits, or horse-shoes which are used with the game should also be made of or coated with rubber, so that no metal parts may come in contact with or deface the polished surfaces of floors or tables, on which the base may be placed in playing the game, and the rubber rings, quoits or horse-shoes of course will not injure such surfaces even if they strike the same during 35 playing of the game.

The construction shown in Fig. 3 illustrates the use of a larger base or web portion 1, but I do not consider the invention in its broader aspect restricted to the specific construction of base described, but the particular construction of base described is very useful and important, in that it insures the base will adhere by suction to any flat surface on which it is placed.

45 What I claim is:

1. In a game apparatus of the character specified a flexible non-metallic base member having a substantially thickened upstanding central boss having a hole for a 50 pin and a plurality of equidistant studs adjacent the periphery of the base.

2. In a game apparatus of the character specified a flexible non-metallic disk having a central substantially thickened upstanding integral boss provided with a socket, and a vertical pin retained in the socket by 55 the resiliency of the boss.

3. In a game apparatus of the character specified a flexible non-metallic disk base having a substantially thickened central upstanding integral boss provided with a

socket, a vertical pin retained in the socket by the resiliency of said boss, and studs projecting from the upper side of the base adjacent the periphery thereof.

65

4. In a game apparatus of the character specified a flexible, non-metallic disk having a central substantially thickened upstanding boss provided with a socket; a plurality of studs projecting from the upper side of the base adjacent the periphery thereof, and a vertical pin detachably engaged with said socket and retained therein by the resiliency of the boss.

70

5. In a game apparatus of the character specified a base member having a substantially thickened upstanding central boss provided with a socket, and a plurality of equidistant studs adjacent its periphery and a pin detachably attached to said boss, said base and studs being formed integral of 75 molded rubber.

80

6. In a game apparatus of the character specified a base having a central upstanding stud formed of resilient material, said stud having a socket provided with an enlarged recess at its bottom, and a pin adapted to engage the socket and having an enlargement or head on its lower end adapted to engage the enlargement in the bottom of the 90 socket, whereby the pin is detachably but firmly held in engagement with the base.

85

7. In a game apparatus of the character specified a base having a plurality of equidistant studs on its periphery and a central upstanding stud formed of resilient material, said stud having a socket provided with an enlarged recess at its bottom, and a pin adapted to engage the socket and having an enlargement or head on its lower end 100 adapted to engage the enlargement at the bottom of the socket, whereby the pin is detachably but firmly held in engagement with the base.

95

8. In a game apparatus of the character specified a flexible non-metallic base having a plurality of equidistant studs on its periphery and a central upstanding stud having a socket provided with an enlarged recess at its bottom, and a pin adapted to engage the socket and having an enlargement or head on its lower end adapted to engage the enlargement at the bottom of the socket, whereby the pin is detachably but firmly held in engagement with the base; said base having a thin annular portion surrounding the central stud and between said stud and the longitudinal studs.
